[57] CLAIM

The ornamental design for a bottle, as shown and described.

DESCRIPTION

FIG. 1 is a perspective view of a bottle showing my new design;

FIG. 2 is a top plan view thereof drawn to a scale enlarged from that of FIG. 1;

FIG. 3 is a side elevational view thereof, the opposite side being the same in appearance;

FIG. 4 is a front elevational view thereof, the rear elevational view being the same in appearance; and

FIG. 5 is a bottom plan view thereof.
